UNITED STATES PATENT OFFICE.

WILLIAM JUDSON SMITH, OF ST. PAUL, MINNESOTA.

HEATING SYSTEM FOR ELECTRIC-RAILWAY CARS.

Application filed August 25, 1922. Serial No. 584,212.

To all whom it may concern:

Be it known that I, WILLIAM J. SMITH, a citizen of the United States, residing at St. Paul, in the county of Ramsey and State 5 of Minnesota, have invented certain new and useful Improvements in Heating Systems for Electric-Railway Cars, of which the following is a full, clear, and exact description, such as will enable others skilled in the art 10 to which it appertains to make and use the same.

This invention relates to a heating system for railway cars and more particularly to an air heating system for electric railway 15 cars.

This invention has for its general object an improved heating system for railway cars which is safe, efficient, economical and readily installed.

20 A more specific object for this invention is to provide a system of heating in which air is the heating medium, the system being provided with means exterior to the car body for heating the air.

25 Another object is to provide a system for electric railway cars in which the air is heated by the energy dissipated in the motor rheostats.

Still another object is to provide an improved housing for the motor rheostats which conserves the heat for heating purposes and yet affords provision for the proper cooling of the rheostats in hot as 30 well as in cool weather.

35 Other objects of this invention will in part be hereinafter specifically pointed out and in part obvious from the arrangements and constructions here set forth.

The invention accordingly consists in the 40 features of construction, combinations of elements and arrangement of parts which will be exemplified in the construction hereinafter set forth, and the scope of their application will appear in the appended claims.

45 For a more complete understanding of the nature and advantages of this invention reference should be had to the following detailed description, which describes the best 50 illustrative embodiment of this invention at present known to me, taken in connection with the accompanying drawing in which:

Figure 1 shows an electric street railway

car, mainly in side elevation, provided with the heating system in accordance with this 55 invention;

Fig. 2 is a plan view of the car shown in Fig. 1;

Fig. 3 shows a view partly in section and partly in side elevation of the heating means 60 for containing the motor rheostats which heat the air supplied to the car;

Fig. 4 is a vertical section taking on a plane at right angles to that of Fig. 3, and further illustrating the construction of the 65 heating means containing the rheostats;

Fig. 5 is a fragmentary view showing the end doors of the heating means;

Figs. 6 and 7 are fragmentary views 70 showing details of the door latching means; while

Fig. 8 shows a transverse section of the car shown in Fig. 1 equipped with this invention.

Referring now to the drawing, and particularly to Figs. 1 and 2, 10 denotes a car body the interior of which is heated by air supplied thereto through the heat distributing conduits 11, (indicated in broken lines in Fig. 1). These conduits are supplied 80 with heated air received from, and communicate with the heating means 12, shown as secured exterior to the car body and preferably below the car floor 13. The conduits 11 are arranged to discharge into the car 85 body at a plurality of points so disposed as preferably to get the circulation of the heating medium to all points of the car body; such discharge points as illustrated may be conveniently located adjacent the roof of the 90 car, as designated at 14.

The movement of the heated air within the conduit 11 and its discharge into the car body, may be accelerated by the employment of the small air injecting means shown 95 at 15, which comprises tubular passages extending to the exterior of the car having outwardly flared funnel shaped mouths 16, the tapered inner end 17 of which project into the conduits 11 in the direction of a 100 discharge opening 14. It is seen that this accelerating means operates on the principle of the injector drawing air from the outside which passes into the conduit 11 in the form of a small rapidly moving stream 105 moving in the direction of the outlet of the

conduit, thereby entraining and imparting movement to the column of air within the conduit 11.

The air distributed within the car body is preferably returned to the heating means 12 to be re-heated, thereby providing for the complete circulation of the heating medium. This return is conveniently effected by means of a conduit disposed adjacent the floor of the car body as shown at 18 in Fig. 8. This conduit 18 has a mouth 19 projecting slightly above the level of the car floor, opening to receive the cool air which has settled to the floor of the car. The conduit 18 leads to and discharges into the heating means 12 at one side as indicated at 20.

The air heating means, exterior to the body of the car, is shown more in detail in Figs. 3, 4 and 5; and comprises a box-like body 22 preferably constructed with a double sheet metal wall, as indicated at 23, between which a filling of heat insulating material, such as asbestos, 24 is disposed. This heating means is supported from the floor 13 of the car body by means of the frame work shown at 25. Extending up from the top of the body of the box 22 is the hollow tubular connection 26 which enters and is supported by the floor 13. This tubular connection is designed to conduct a minimum of heat to the floor of the car body. Within this tubular connection extends the air outlet conduit 27 which communicates with and leads from the heating chamber 28, entering at the top of the box 22. This conduit 27 communicates with the lower end of the heat distributing conduit 11, to supply it with heated air. The connection 20 of the conduit 18 is shown as discharging into one side of the box 22 behind the deflector 29.

Within the box 22 are supported in insulated relation a plurality of rheostats 30. These rheostats have electrical connections 31 leading to the motors of the car, and are adapted to supply the starting and controlling resistance for the car motors. These rheostats consequently dissipate a quantity of electrical energy in the ordinary run of the car, this energy being dissipated in the form of heat which is imparted to the body of air in the chamber 28 of the box 22.

In summer, when it is not desired to supply heated air from the chamber 28 to the car, box 22 is provided with a valve plate 35 adapted to be slid across the mouth of the outlet conduit 27, thereby preventing the passage of air to the interior of the car.

In order, however, to provide sufficient ventilation to cool the rheostats 30 when not heating air for heating purposes, the passage of sufficient air for cooling purposes over the rheostats 30 is afforded by opening the swinging doors 36 and 37 on the ends of the box 22. These doors are shown in Fig.

3 as hinged along their upper edge and extend substantially the full width of the box 22, these doors being formed with the double wall construction of the box and filled with insulating material 24. These doors 36 and 37, when opened and fastened up to the floor 13 of the car body, admit the passage of air over the rheostats directly from the outside atmosphere, the flow of this air being accelerated by the motion of the car. Deflectors 75 may be provided as indicated at 38 for controlling the flow of air over the rheostats when the doors 36 and 37 are opened.

The box 22, as thus constructed, is of a heat insulating character preventing the radiation to the outside of substantially all the heat dissipated by the rheostats 30. The body of air being circulated through the car body is thus adapted to absorb substantially all the energy in the form of heat dissipated, thereby operating to obtain a very high efficiency and low cost in the heating of railroad cars.

In order to prevent drafts of air from passing through the body of the box 22 when the doors 36 and 37 are closed special fastening means are provided for the doors in order to make them substantially air tight when closed. The details of this fastening means are shown in Figs. 6 and 7. The bottom of the door at 36, as shown in Fig. 7, is adapted to close snugly into place and fit tightly on the bottom 40 of the box 22, the floor being slightly offset and chamfered as indicated at 41 to permit the thick door to be swung into place. The fastening means comprises the link 42 which engages with the hook 43 on the bottom 40, this link being operated by the hand lever 44 pivoted at 45 to the bottom of the door 36. The lever 44 when swung to the upper position indicated throws the link 42, when engaging with the hook 43, past the dead center above the pivot 45, thereby insuring a tight fastening which will not jar loose during the operation of the car.

The object in chamfering the box 22, as shown at 41, is to provide a recess which may be filled with plastic asbestos cement. This filling will take up any wear there may be on the floor or door, or in stretching of lock links. Enough cement will be put in to make the joint air tight. This could be done in the fall, and the filling could remain until spring, unless it were necessary to remove a rheostat.

In operation it is seen that when it is desired to heat the car, the doors 36 and 37 would be secured in their closed position with the valve at 35 open. The energy dissipated by the rheostats 30 would heat the air within the chamber 28 which flows through the distributing means to the interior of the car where it circulates to heat the car. When finally cooled it settles to

the bottom of the car to be returned through the conduit 18 to the box 22. In summer, however, when it is necessary to cool the rheostats without heating the car, the valve 35 is put in place, and the doors 36 and 37 opened to the extent desired to secure the necessary cooling effect.

It will also be perceived, that by removing the heating means to the exterior of 10 the car, that a more commodious arrangement is afforded, and fire hazard is considerably reduced, making for a cleaner and safer method of heating.

As many changes could be made in the 15 above construction and as many apparently widely different embodiments of this invention could be made without departing from the scope thereof, it is intended that all matter contained in the above description or 20 shown in the accompanying drawings shall be interpreted as illustrative and not in a limiting sense.

It is also to be understood that the language used in the following claims is intended 25 to cover all of the generic and specific features of the invention herein described, and all statements of the scope of the invention which, as a matter of language, might be said to fall therebetween.

30 Having described my invention, what I claim is new and desire to secure by Letters Patent, is:

1. In a heating system for electric railway cars, the combination with means for 35 distributing heated air within the car, of means for heating the air supplied to said distributing means by the energy dissipated in the motor rheostats, and positive means in said distributing means for accelerating 40 the movement of the heated air.

2. In a heating system for electric railway cars, the combination with means for distributing heated air within the car, of 45 means for heating the air supplied to said distributing means by the energy dissipated in the motor rheostats, means for returning the air to said heating means, and positive means in said distributing means for accelerating the movement of the heated air.

50 3. In a heating system for electric railway cars, the combination with conduits for distributing heated air to the interior of the car, of a heat insulated box suspended beneath the car adapted to house the motor rheostats and supply heated air to said conduits, and positive means for accelerating the movement of air in said distributing conduits.

55 4. In a heating system for electric railway cars, the combination with conduits for distributing heated air to the interior of the car, of a heat insulated box suspended beneath the car adapted to house the motor rheostats and supply heated air to said conduits, a conduit having an opening near the

floor of said car and leading to said box adapted to withdraw the cooled air from the car, to be re-heated by said rheostats, and means disposed in said distributing conduits adapted to entrain air by the motion 70 of the car and accelerate the movement of heated air through said distributing conduits.

5. In a heating system for electric railway cars, the combination with conduits for 75 distributing heated air to the interior of the car, of a heat insulated box suspended beneath the car adapted to house the motor rheostats and supply heated air to said conduits, a conduit having a receiving opening 80 near the floor of said car and leading to said box, and positive means for accelerating the movement of air in said distributing conduits.

6. In a heating system for electric railway cars, the combination with conduits for distributing heated air to the interior of 85 the car, of a heat insulating box suspended beneath the car adapted to house the motor rheostats and supply heated air to said conduits, 90 a conduit having a receiving opening near the floor of said car and leading to said box, and funnel shaped air injecting devices having their mouths on the exterior of said cars and pointing in the direction the car 95 is to move, and nozzles in said distributing conduits discharging in the direction of an opening in the distributing conduit.

7. In a heating system for electric railway cars, the combination with conduits 100 for distributing heated air within the car, of a double walled box suspended beneath the car floor and opening to the atmosphere, the space between the walls being filled with heat insulating material, motor rheostats within the box, and means disposed in said conduits adapted to entrain air by the motion of the car and to draw it through the box in contact with said rheostats.

8. In a heating system for electric railway cars, the combination with conduits for 110 distributing heated air within the car, of a double walled box suspended beneath the car floor and opening to the atmosphere, the space between the walls being filled with heat insulating material, motor rheostats within the box, a valve controlling the passage from said box to said distributing conduits, and means disposed in said conduits adapted to entrain air by the motion of the 115 car and to draw it through the box in contact with said rheostats.

9. In a heating system for electric railway cars, the combination with conduits for 120 distributing heated air within the car, of a double walled box suspended beneath the car floor and opening to the atmosphere, the space between the walls being filled with heat insulating material, motor rheostats within the box, and funnel shaped air in- 125

jecting devices having their mouths on the exterior of the car and pointing in the direction in which the car is to move, and nozzles connecting with said funnels disposed in said conduits and arranged to discharge in the direction of an opening in the distributing conduits into the car.

10. In a heating system for electric railway cars, the combination with conduits for distributing heated air within the car, of a double walled box suspended beneath the car floor and opening to the atmosphere, the space between the walls being filled with heat insulating material, motor rheostats within the box, means for returning the air distributed within the car to the box, and a funnel disposed on the exterior of the car and pointing in the direction in which the car moves arranged to entrain air, and co-operating nozzles connected to said funnel and arranged to discharge into said conduits in the direction in which said conduits discharge into said car.

11. Air heating means for electric railway cars comprising a heat insulating box adapted to be suspended beneath the car and to house the motor rheostats, said box having a valved passage adapted to lead to air distributing means within the car, and a return passage arranged to supply the air to be re-heated at points adjacent the rheostats, remote from said valved passage.

12. Air heating means for electric railway cars comprising a heat insulating box adapted to be suspended beneath the car and to house the motor rheostats, said box having a valved passage leading from its top, a return passage leading to its side, and a deflector with the box position to deflect the returning air to points beneath the rheostats.

13. Air heating means for electric railway cars comprising a heat insulating box adapted to be suspended beneath the car and to house the motor rheostats, said box having a valved passage adapted to lead to air distributing means within the car, a return passage, and doors disposed at opposite ends adapted to be opened for ventilating purposes when said valved passage is closed.

14. Air heating means for electric railway cars comprising a heat insulating box adapted to be suspended beneath the car and to house the motor rheostats, said box having a valved passage adapted to lead to air distributing means within the car, a return passage, and double walled doors disposed at opposite ends adapted to be clamped in airtight closed position and retained in open position for ventilating purposes when said valved passage is closed.

15. Air heating means for electric railway cars comprising a heat insulating box adapted to be suspended beneath the car and to house the motor rheostats, said box having a valved passage adapted to lead to air distributing means within the car, a return passage, and double walled front and rear doors filled with heating insulating material and provided with clamps having engagement members adapted to be snapped in clamping position past dead centres, and means for retaining said doors in open position for ventilating purposes when said valved passage is closed.

In testimony whereof I affix my signature, in the presence of two witnesses.

WILLIAM JUDSON SMITH.
